PROCESS FOR RECOVERY AND PURIFICATION OF CYCLODIENES FROM CRACKED PETROLEUM

Samuel W. Wilson and Thomas G. Jones, Baton Rouge, La., assignors to Esso Research and Engineering Company, a corporation of Delaware

Application January 17, 1952, Serial No. 266,914

4 Claims. (Cl. 260—666)

This invention is concerned with processing of cracked petroleum hydrocarbon streams containing C₅ and C₆ cyclodienes.

An object is to isolate the cyclodienes, particularly cyclopentadiene and methyl cyclopentadiene, as monomers in effecting their purification and to recover these monomers from fractions of cracked petroleum naphtha containing the cyclodienes as monomers, dimers, and codimers mixed with other unsaturated hydrocarbons and aromatic hydrocarbons.

The present invention pertains to the following operations:

(1) An initial rough fractionation of the cracked naphtha is carried out at relatively low temperatures (e. g., below 175° F.) and with short hold-up time in obtaining a distillate fraction of C₄—C₉ hydrocarbons and a residual fraction of C₅—C₁₂ hydrocarbons.

(2) Stripping of additional C₅—C₉ hydrocarbons from the residual C₅—C₁₂ fraction is accomplished at relatively higher temperatures (e. g., at 240° F. to 410° F.) than the initial fractionation to insure removal of C₅—C₆ components from this residual fraction in which dimers and codimers are concentrated.

(3) Processing of the lightest fractions for eliminating C₄ and lower hydrocarbons is carried out at lower temperatures (e. g., at below 160° F.) for protection against interpolymerization.

(4) Processing of the streams of C₅—C₉ hydrocarbons to selectively dimerize the cycladiene components and recover the resulting dimers as a residual fraction diluted with a restricted amount of C₇—C₉ hydrocarbons is carried out at moderate temperatures (e. g., at below 260° F.), preferably with the aid of steam, to minimize decomposition of the dimers.

(5) Depolymerization of C₁₀—C₁₂ dimers and codimers diluted with restricted amounts of C₇—C₉ hydrocarbons in the residual streams is carried out at appropriate high temperatures mainly above 350° F. and preferably in consecutive stages at 380° to 410° F. and 390° to 420° F.

It is known that some processes have dealt only with recovery of cyclopentadiene from coal tar light ends, and others have dealt with recovery of cyclopentadiene from certain low boiling fractions of cracked petroleum distillates.

The cyclodienes present in highly cracked petroleum distillates have now been analyzed as being present in a number of homologs and polymeric forms, for example, the monomers of C₅ and C₆ cyclodienes, their higher homologs, also, the dimers, codimers, higher polymers of these homologous cyclodienes, and interpolymers with other diolefins. The dimer and codimer forms are stable at ordinary atmospheric temperatures but on being heated to elevated temperatures of the order of 280° F. and higher they start to undergo cracking or depolymerization. The monomeric forms are unstable even at ordinary temperatures and undergo polymerization as they are heated to temperatures above 140° F. On account

of the various forms in which the cyclodienes tend to be present in highly cracked naphtha distillates, there have been problems of determining the best manner of segregating a maximum amount of the cyclodienes desired and recovering them as monomers of highest purity.

In the past, the processes for the recovery of cyclopentadiene from cracked petroleum naphthas have been represented by operations which went to two somewhat opposite extremes.

(1) In one type of prior art process, attempts were made to depolymerize all of the cyclopentadiene dimer, first in a wide boiling range naphtha including hydrocarbons lower and higher than C₅ hydrocarbons, after which the cyclopentadiene monomer together with other C₅ and lower unsaturated hydrocarbons were separated from higher hydrocarbons (C₆ and up); then the cyclopentadiene monomer was dimerized in the presence of C₅ and lighter hydrocarbons. That type of process was found unsuitable for the present objects. It omitted recovery of cyclopentadiene with methyl cyclopentadiene from their codimers, and resulted in the formation of a highly contaminated product, contamination being apparently due to the dimerization in the presence of highly reactive C₄ unsaturated hydrocarbons. The other type of process which went toward an opposite extreme for obtaining greater purity, eliminated the cyclopentadiene monomer with other C₅ and lighter hydrocarbons from the cracked naphtha distillate, so as to leave cyclopentadiene dimers highly diluted in an aromatic naphtha portion of the initial cracked naphtha and thereafter the dimer was decomposed to monomer in this aromatic fraction so that the final monomer could be fractionally distilled away from the higher boiling hydrocarbons.

The type of operation which is particularly suitable for obtaining a concentrate of the cyclodienes in accordance with the present invention is distinguished from each of the above described opposite extremes, because the present invention particularly requires obtaining a concentrate in which C₆ as well as C₅ cyclodienes are recovered to the greatest extent possible, as dimers and codimers substantially free of other hydrocarbons except for a restricted amount in the C₇ to C₉ range.

In order to obtain the cycladiene dimer and codimer concentrates, the following division of fractions is employed:

(a) A light naphtha distillate cut I rich in C₅—C₆ components is readily separated from the cracked naphtha distillate if this stream is allowed to contain some C₄ components and components in the C₇ to C₉ range. This light naphtha stream is subjected to fractionation mainly at low temperatures, e. g., by compressing, cooling, and stripping to eliminate substantially all the C₄ and lighter hydrocarbons. With C₄ and lighter hydrocarbons eliminated, the remaining C₅—C₆ portion of this cut I can be soaked to dimerize said monomers, then can be fractionated at moderate temperatures to obtain a concentrate of C₁₀—C₁₂ dimers and codimers with restricted amounts of C₇ to C₉ hydrocarbons.

(b) The heavier cracked naphtha residual fraction of C₅ to C₁₂ range contains some cyclopentadiene monomer as well as methyl cyclopentadiene monomer, but it will also contain substantial amounts of the C₅ and C₆ cyclodienes in the form of C₁₀—C₁₂ dimers and codimers. By subjecting this cut to fractional distillation under conditions suitable for distilling therefrom a fractional distillate principally including the C₅ and C₆ cycladiene monomers with minor amounts of C₇ to C₉ hydrocarbons, a very good recovery is obtained from the decomposition of the dimers and codimers. This C₅—C₆ rich distillate cut is very close in its composition to the above described C₅—C₆ rich fraction from cut I with C₄ and lower elimi-

nated. Accordingly, either of the C₅-C₆ rich fractions or a combination thereof serves as a suitable feed stock for the remaining operational steps which include first a thermal soaking or dimerizing of the cyclodiene monomers present into dimers and codimers, followed by a fractionation step to remove C₅ to C₉ hydrocarbon components from the C₁₀-C₁₂ cyclodiene polymers concentrate containing a minor amount of C₇ to C₉ hydrocarbons.

Next, the cyclodiene residual dimer concentrates are subjected to liquid phase depolymerization preferably in at least two stages at appropriate temperatures with rapid removal of monomers formed by decomposition of the polymers in order to minimize the reverse polymerizing reaction and assure depolymerization of the codimer.

(c) In a dual or multiple stage liquid-phase cracking or depolymerization, the cyclodiene dimer concentrate with controlled dilution by C₇-C₉ hydrocarbons is kept as free as possible of other types of reactive unsaturated hydrocarbon compounds and the cyclodiene polymers, mainly C₁₀-C₁₂ dimers and codimers, subjected to the liquid phase cracking are prevented from being diluted excessively by hydrocarbons which would prevent the temperature from being raised to a suitable high degree. The C₅ and C₆ cyclodiene monomers that are stripped out as fast as they are formed in each of the cracking stages are immediately and quickly passed to a fractionation zone to recover distillates of the C₅ and C₆ cyclodienes having a high purity. It is essential that a limited amount of inert hydrocarbons, especially in the C₇ to C₉ range, be present to aid in stripping the monomers and for keeping the monomers diluted during their fractionation. The distillate bottoms from the fractionating zone will contain some C₅ and C₆ cyclodiene dimers and codimers with heavier polymers, but since it is desirable to prevent excessive accumulation of low boiling hydrocarbons which would prevent the desired high depolymerization temperatures from being maintained there has to be a purge of such materials. Also, a purge of higher cyclodiene polymers which resist dissociation, as the distillate bottoms are recycled to the cracking zones.

The general principles of the operations employed in the present invention have been described, and more details will be given with reference to the accompanying drawings together with specific examples.

In the drawing the general flow plan is shown for obtaining the feed stock to be used in the depolymerizing operation and final purification.

In the simplified flow plan shown in the drawing, a wide-boiling range cracked naphtha distillate stream is represented as coming from a high temperature vapor phase cracking plant through line 1. The present invention is not particularly concerned with the method of cracking petroleum and of obtaining the naphtha distillate stream; therefore, it is sufficient to state that petroleum hydrocarbons boiling in the range of 250°-700° F. are cracked in the vapor phase at 1000° F. to 1600° F. for a short period of 1 to 5 seconds, preferably in the presence of 50 to 90 mole per cent steam based on the hydrocarbon feed and under a pressure of 1 to 10 atm. The naphtha distillate distilled from the cracked petroleum will be of approximately C₁-C₁₂ range and will contain C₅ and C₆ cyclodienes in various forms, monomers, dimers, and codimers, together largely with unsaturated aliphatic hydrocarbons and aromatic hydrocarbons within this range. The naphtha distillate may be a condensed distillate which is free of the normally gaseous C₁-C₃ hydrocarbons or may be maintained in the vapor phase, including some normally gaseous hydrocarbons.

The naphtha distillate essentially containing components within the C₅-C₁₂ range is passed by line 1 into what will be termed a "splitting unit," such as a conventional fractionating column 2, for making a split between an overhead C₄-C₉ stream (cut I) and a resi-

dual C₅ to C₁₂ stream (cut II). It is to be noted that this split is not made with exacting limits, and thus the overhead (cut I) stream tends to contain hydrocarbons lower than C₅ up to C₉ hydrocarbons while the residual cut II stream also contains some C₅ to C₉ components. This rough splitting between the two cuts is desirable not only for the sake of economy, but also for a number of other reasons. The rough splitting between the two cuts mentioned reduces opportunities for interpolymerization of the cyclodienes with the aliphatic diolefins and satisfactorily segregates the two types of material which are to be further processed.

Suitable operation conditions in the cut splitting operation, such as carried out in fractionating column 2, are as follows:

No. of plates	6.
Overhead vapor temperature	60° to 100° F.
Pressures	20 to 55 p. s. i. g.
Maximum bottoms temperatures	175° F.
Holdup time of liquids below feed plate	1 to 5 minutes
	3.

The overhead (cut I) stream removed through line 3 from the splitter unit 2 is subjected to relatively low temperature operations for eliminating C₄ and lighter hydrocarbons. These relatively low temperature operations may include compression and cooling by means of compressor 4 and heat exchanger 5 in line 3, but finally in the fractionating column 6, the higher boiling residual portion of the cut I stream is separated as a bottoms product substantially free of C₄ and lower boiling hydrocarbons. The eliminated C₄ and lighter hydrocarbons are removed in the overhead stream line 7 from the column 6.

Column 6 is used purposely to remove the C₄ and lighter hydrocarbons under conditions which give very little opportunity for interpolymerization between the reactive C₄ unsaturates and the cyclodienes that are to be concentrated in the liquid residue. In general, the conditions of operation in column 6 are as follows:

Vapor overhead temperature	35° F. to 62° F.
Pressures	5 to 20 p. s. i. g.
Bottoms temperatures	135° F. to 160° F.
Holdup time below feed plate	5 to 15 minutes.

The residual bottoms are withdrawn from column 6 through line 8. This residual bottoms portion of the cut I stream should in general have an ASTM distillation range of about 96° F. to 344° F., the high end point being due to the presence of some dimerized cyclodienes. It is interesting to note also that this residual portion of the cut I stream contains relatively small amounts of C₅ and higher hydrocarbons other than methyl cyclopentadiene and the cyclodiene dimers; for example, only about 10 weight percent of such other C₅ to C₉ hydrocarbons, including about 3 weight percent benzene. Therefore, in this residual portion of cut I, the C₅ and C₆ cyclodiene monomers are present in suitably higher concentration to undergo dimerization quite readily on being heated to a moderate soaking temperature of about 150° F. to 240° F. in a period of 12 to 6 hours.

From the splitting unit 2, the residual cut II stream is withdrawn as bottoms through line 9 to be sent into a relatively higher temperature stripping zone 10. The purpose of the higher temperature fractionating zone 10 is to distill over mainly a C₅-C₉ distillate which will include the C₅-C₆ cyclodiene monomers initially contained in the cut II stream and also such monomers evolved from the dimers and codimers of the cyclodienes present in the cut II stream of C₅ to C₁₂ hydrocarbons.

Heat is indicated to be supplied to bottoms of the fractionating zone 10 by the heater 11. In this high temperature fractionating zone an incipient depolymerization temperature is desirable. Therefore, the holdup time can be prolonged and there is nevertheless slight opportunity for interpolymerization between the cyclodienes and ali-

phatic unsaturates since the unsaturates in the cut II stream are relatively high molecular weight and less reactive than the aliphatic unsaturates in the aforementioned cut I stream. The desired cyclodiene monomer stream is taken overhead from fractionating zone 10 by line 12. For simplification, the cyclodiene monomer overhead stream from fractionating zone 10 is shown to be joined with the residual portion of the cut I stream withdrawn by line 8 from fractionating column 6, thence to be subjected to a dimerization in a soaking unit 13, although each of these streams could be separately subjected to dimerizing and later fractionation.

Typical operating conditions for obtaining the C₅ and C₆ cyclodiene monomer bearing distillate from the cut II stream of C₅ to C₁₂ range, as in the high temperature stripping zone 10 are as follows:

Vapor overhead temperature	.....	°F	240
Pressure	.....	p. s. i. g.	60
Bottoms temperature	.....	°F	410
Holdup time of liquid below feed plate—minutes	.....	30-60	20

The residual liquid bottoms of the fractionating zone will contain hydrocarbons higher than C₇, including cyclodiene polymers which did not undergo decomposition.

The soaked liquid products containing substantially all the cycladienes in the form of dimers and codimers are passed from the soaking unit 13 into a fractionating column 15 by line 16.

The purpose of the fractionating column 15 is to separate the polymers of the cycladienes, dimers, and codimers, as a residual bottoms concentrate that can be removed through line 17. To obtain this concentrate, the other hydrocarbons are distilled overhead from column 15 and withdrawn through line 18 to the fullest extent possible without incurring loss of the cycladienes by depolymerization. Therefore, column 15 is operated under such conditions that minimize depolymerization of the cycladiene polymers while distilling therefrom the other types of C₅ through C₉ hydrocarbons that are present. In doing this, however, it has been found desirable from a practical viewpoint to leave a restricted amount of such other hydrocarbons with the polymers of the cyclopentadiene. A suitable restricted amount of such other types of hydrocarbons is of the order of 10 to 30 weight percent and mainly such hydrocarbons in the C₇ to C₉ range. Accordingly, column 15 is operated under the following represented conditions:

Number of plates	.....	15	
Overhead temperature	.....	°F	145
Pressure	.....	p. s. i. g.	6
Bottoms temperatures	.....	°F	260
Holdup time	.....	minutes	30

The distillation in column 15 is advantageously carried out with introduction of steam by line 19.

The next phase of the overall operation which will be described pertains to the liquid phase depolymerization treatments and associated fractionation of the cyclopentadiene and methyl cyclopentadiene monomers that are to be recovered as a pure distillate.

The cyclodiene polymer concentrate which is withdrawn as bottoms from column 15 through line 17 is sent to a first stage of the first cracking or depolymerizing vessel 20. Residual liquid from the high temperature stripper is sufficiently free of cyclodiene dimers and may be removed by line 45.

Vapors evolved from the liquid polymer concentrate in vessel 20 are to be rapidly withdrawn therefrom. The liquid polymer concentrate in vessel 20 has to be maintained at a sufficiently elevated temperature, above 350° F., for accomplishing the depolymerization while the liquid is boiling under a pressure that maintains the cyclodiene polymers in liquid phase, e. g., a moderate pressure of 2 to 20 p. s. i. g. Increased pressures favor the repolymerization of cyclodiene monomers and are, therefore, to be avoided. Accordingly, the vapors taken overhead from

vessel 20 should principally comprise the C₅ and C₆ cyclodiene monomers with a minor volume proportion of C₇-C₉ hydrocarbons that beneficially act as diluents and stripping agents.

5 The vapors taken overhead from vessel 20 may be passed up through a superimposed refluxing zone but they should be passed quickly by line 26 to the fractionating column 27. Practically all the C₅ and C₆ cyclodiene monomer vapors are to be carried rapidly with C₇ to C₉ hydrocarbon vapors to the fractionating column 27.

In fractionating column 27, the vapors from line 26 undergo fractionation on passing upwardly through 5 to 10 plates at temperatures of the order of 175° F. to 160° F. In this fractionation, C₇ to C₉ hydrocarbons with a small amount of cyclodiene dimers formed through repolymerization are condensed to liquid which flows to the bottom of column 27. The C₅ and C₆ cyclodiene monomers in purified form reach the upper plates of fractionating column 27 at temperatures of 150° to 160° F. and then may be distilled overhead for further fractionation, or a mixed monomer distillate may be condensed and collected.

Overhead distillate from fractionator 27 may be passed by line 28 into a subsequent fractionator 29, wherein the C₆ cyclodiene is condensed and recovered as a bottoms fraction withdrawn by line 30. The cyclopentadiene or C₅ cyclodiene monomer vapor is recovered as a distillate as it is passed through overhead line 31, then through cooling condenser 32 and collected in receiver 33. Some refluxing of cyclopentadiene distillate from receiver 33 through line 34 to the upper part of fractionator 29 is helpful in making a sharper separation between the individual monomer products. The cyclodiene product is removed by line 35.

35 The fractionator 29 is operated at temperatures between a bottoms temperature of about 160° F. and a top temperature of about 120° F.

The second stage depolymerizing vessel 36 receives residual cyclodiene polymer liquid from vessel 20 through line 37 and is advantageously operated at a higher depolymerization temperature. Heat may be supplied to vessel 36 by suitable heating means, e. g. heating coil 38 and a heat exchanger 39 for supplying heat to recycled bottoms condensate from fractionator 27 as this concentrate is returned through line 40 and line 41 to vessel 36.

40 Control of the liquid recycle from the bottom of fractionator 27 to either vessel 20 or 36, or to both, is necessary to prevent accumulation of relatively low-boiling C₇ to C₉ hydrocarbons in these vessels. Therefore, to avoid excessive buildup of these relatively lower-boiling hydrocarbons, some of the reflux being recycled through line 40 is purged through a withdrawal line 42 or withdrawal line 43 from vessel 36. The cyclodiene monomer vapors are withdrawn overhead as rapidly as possible from vessel 36 and may be passed directly by line 44 to join the stream of vapors in line 26 entering the fractionator 27. The vapors leave the vessel 36 at a temperature of about 350° F. to 380° F.

45 The following factors guide the selection of operating conditions during the depolymerizing treatment of the cyclodiene polymer concentrates:

(a) The depolymerization of the polymer concentrates is negligible until the temperature of the liquid concentrate is maintained at above 350° F.

50 (b) The cyclodiene monomers have to be stripped from the liquid concentrate as fast as they are formed with the aid of a limited amount of C₇ to C₉ hydrocarbons since excessive amounts of these intermediate boiling hydrocarbons would lower the temperature in the depolymerization zone.

55 (c) After a substantial amount of the cyclodiene dimers undergo depolymerization in the concentrate, it is necessary to increase the depolymerization temperature, e. g. to above 380° F., to accomplish further depolymerization at a suitable rate.

(d) The monomer bearing vapors being transferred from the depolymerization zones to a fractionation zone have to be substantially free of other close-boiling hydrocarbons, especially other C₅-C₇ hydrocarbons boiling up to about 175° F., so that the separation of these monomers by fractionation can be carried out most expeditiously with quick cooling in order to avoid recombination of the monomers into dimers and higher polymers that have greater thermal stability than the dimers and make this recovery of the available cyclodienes.

Summarized results of continuous two-stage liquid phase depolymerization runs on cyclodiene polymer concentrates are given in the following tabulation:

TABLE

Continuous two-stage operation

FEED: Concentrate of 67.7 weight per cent dimerized cyclodienes with C₅-C₉ hydrocarbons.

CONDITIONS: Feed charged continuously to two-stage unit for 8-10 hours total residence time. Vapors were removed from each depolymerizing vessel continuously to 5th plate of a 20 plate Oldershaw column held at 160° F. overhead temperature. Bottoms of column were recycled to first stage. Purge was taken from second stage to hold unit in balance.

Total Run Length, Hrs.	Depolymerization Temp., ° F.		Recovered Product		
	1st stage	2nd stage	Wt. Percent Yield of Monomers on Crude Feed	Purity, Wt. Percent	Recovery, Wt. Percent, Based on Available Cyclodiene
12.....	350	350	0	92.2	75.2
13.....	380	390	59.3	93.2	85.9
14.....	390	400	56.8	93.2	85.9
14.....	400	410	57.7	96.1	89.5
13.....	410	420	64.6	89.2	83.4

The data of the table showed quite emphatically that the temperature required for satisfactory recovery and high purity are substantially above 350° F., preferably in the range of 380° to 410° F. and 390° to 420° F. for the second stage.

The feed used in making the runs shown in the table was a concentrate obtained by first combining a C₅-C₉ light cracked naphtha fraction with a C₅-C₉ cracked naphtha fraction, dimerizing the combined fractions at 240° F. for 6½ hours, then fractionating to remove mostly light C₇ and lower boiling hydrocarbons from the residual concentrate. The operation rate tolerated recycling up to 18 weight % of the cracker product fractionator bottoms from column 27 based on the fresh feed.

Reviewing features of the process described in comparison to other types of processes, the advantages of the presently developed process were determined to be considerable with regard to higher recovery of the monomers with high purity at lower investment cost.

The added amount of cyclodiene polymer in the concentrate from the separately treated low-boiling distillates (of C₅-C₉ range) gave a 50% increase in yield of recovered cyclodiene monomers. This increase in yield is accounted for particularly by recovery of cyclopentadiene with methyl cyclopentadiene from a large part of their monomers and polymers and partly by repression of interpolymerization of the cyclodienes with the reactive dienes present in the low boiling C₄ to C₉ streams handled at low temperatures.

The stage-wise cracking of the concentrated cyclodiene polymers at elevated temperatures above 350° F. in the presence of limited amounts of C₇ to C₉ hydrocarbons permitted maintenance of the elevated temperatures in the depolymerization and reduced the purging, thus making a saving in depolymerizing and fractionating equipment and thus lowering the loss of polymers in the purge. In the stage-wise cracking, the temperature maintained in any stage may be between 350° F. and 450° F., but the temperature should be at least above 380° F. in one stage to obtain efficient depolymerization.

Having described the invention it is claimed as follows:

1. In recovering C₅ and C₆ cyclodienes from cracked petroleum naphtha, the steps which comprise distilling from the naphtha a C₄ to C₉ hydrocarbon cut at temperatures below 175° F., removing C₄ hydrocarbons from the C₄ to C₉ cut at temperatures below 160° F. to obtain a remaining C₅ to C₉ hydrocarbon fraction, soaking said C₅ to C₉ hydrocarbon fraction at temperatures of about 150° F. to 240° F. until the cyclodienes in said fraction are dimerized, fractionally distilling C₅ to C₉ components from the resulting soaked fraction to obtain the cyclodiene dimers as a concentrate substantially free of C₆ and lower-boiling hydrocarbons, passing a high boiling residual portion of said initial cracked naphtha containing C₅ to C₁₂ hydrocarbons into a high temperature stripping zone, stripping said residual naphtha fraction of additional C₅ to C₉ hydrocarbons at temperatures between 240° F. and 410° F., soaking said additional C₅ to C₉ hydrocarbons at about 150° F. to 240° F. to obtain more of the cyclodiene dimers, passing the cyclodiene dimers into a depolymerization zone in which the cyclodiene dimers undergo depolymerization at temperatures ranging from above 350° F. to about 450° F., rapidly removing the resulting cyclodiene monomer vapors with higher boiling C₇-C₉ hydrocarbons present in said concentrates to a fractionation zone, and fractionally separating the cyclodiene monomers.

2. In recovering C₅ and C₆ cyclodienes from cracked petroleum naphtha, the steps which comprise fractionally distilling from the naphtha a distillate fraction of C₄ to C₉ hydrocarbons at below 175° F. to obtain a residual fraction of C₅ to C₁₂ hydrocarbons, stripping from said residual fraction at temperatures in the range of 240° F. to 410° F. a C₅ to C₉ distillate fraction containing C₅ and C₆ cyclodienes with some higher components in the C₇ to C₉ range but free of hydrocarbons lower boiling than the cyclodienes, dimerizing the C₅ and C₆ cyclodiene monomers present in said C₅ to C₉ fraction, concentrating resulting C₁₀ to C₁₂ cyclodiene dimers and codimers formed in the C₅ to C₉ fraction and stripping therefrom C₅ to C₉ hydrocarbons until the resulting residual concentrate contains 60 to 90% of said dimers and codimers with less than 40% of hydrocarbons in the C₇ to C₉ range.

3. In recovering C₅ and C₆ cyclodienes from cracked petroleum naphtha, the steps which comprise fractionally distilling at below 175° F. C₄ to C₉ distillation fraction from the naphtha to form a residual C₅ to C₁₂ fraction, stripping additional C₅ to C₉ hydrocarbons from said residual C₅ to C₁₂ fraction at 240° to 410° F., stripping C₄ and lower hydrocarbons from said C₄ to C₉ distillate fraction at below 160° F. to form a second residual C₅ to C₉ fraction, combining said residual C₅ to C₉ fractions, dimerizing C₅ and C₆ cyclodiene monomers present in said combined C₅ to C₉ fractions, concentrating resulting C₁₀ to C₁₂ cyclodiene dimers and codimers formed in said combined C₅ to C₉ fractions by stripping therefrom C₅ to C₉ hydrocarbons until a residue of said combined fractions contains 60 to 90% of the C₁₀ to C₁₂ cyclodiene dimers and codimers with less than 40% of hydrocarbons in the C₇ to C₉ range.

4. In the process defined by claim 3, depolymerizing the C₁₀ to C₁₂ dimers and codimers in said resulting residual concentrate at temperatures in the range of 380° F. to 420° F.
